UNITED STATES PATENT OFFICE

PHILIP KRANZ AND ALBERT P. SCHMID, OF PHILADELPHIA, PENNSYLVANIA, AS
SIGNORS TO BERNARD WILMSEN, OF PHILADELPHIA, PENNSYLVANIA

AUTOMATIC WINDING MECHANISM FOR FRINGE FORMING MACHINES

Original application filed January 7, 1929, Serial No. 330,866. Divided and this application filed September 19, 1929. Serial No. 393,666.

Our invention relates to a new and useful automatic winding mechanism for fringe forming machines, whereby the fringe formed by said machines is automatically wound about a suitable, removable core, during the formation of the fringe and without interruption of the fringe making machine, the present application being a division of a contemporaneously pending case filed by us 10 Serial No. 330,866 filed January 7, 1929.

Our invention further relates to a novel automatic winding mechanism which is adapted to form part of and to be operated or actuated by the driving mechanism of the 15 fringe forming machine proper, without in any way disturbing or interfering with the construction or operation of said machine, the completed fringe being wound automatically in the desired predetermined lengths and without requiring attention on the part 20 of the operator.

To the above ends, our invention consists of a plurality of drums having grooves or 25 seats on the periphery thereof adapted to receive card board blanks or cores, means for detachably retaining said blanks in place, and driving means actuated by the driving mechanism of the fringe forming machine adapted to revolve said drums in 30 timed relation to the formation of the fringe.

It further consists of novel means for simultaneously winding a pair of completed fringes upon a pair of said blanks or cores.

Our invention further consists of various 35 other novel features of construction and advantage all as hereinafter described and claimed.

For the purpose of illustrating our invention we have shown in the accompanying drawings one form thereof which is at present preferred by us, since the same has been found in practice to give satisfactory and reliable results, although it is to be understood that the various instrumentalities of 40 which our invention consists can be variously arranged and organized and that our invention is not limited to the precise arrangement and organization of the instrumentalities as herein shown and described.

In the accompanying drawings:—

Figure 1 represents a fragmentary plan view of a winding mechanism embodying our invention.

Figure 2 represents a front elevation of Fig. 1. 55

Figure 3 represents a perspective view of the core or blank employed in conjunction with the winding mechanism shown in Fig. 1.

Figure 4 represents a side elevation of a clip for retaining the core or blank shown 60 in Fig. 3 in position.

Figure 5 represents a fragmentary view in side elevation showing our novel winding machine applied to a fringe forming machine. 65

Figure 6 represents a perspective view of a portion of the upper right hand end of Fig. 5 showing diagrammatically the manner of sewing and cutting the fringe. 70

Figure 7 represents a length of fringe wound around the core or blank shown in Fig. 3 by means of our novel automatic winding mechanism.

Referring to the drawings in which like reference characters indicate like parts, 1 75 designates the frame or table of a fringe making machine, to which is secured the upright 2, which supports the horizontal brackets 3 which have the front or outer bearings 4 in which are journalled the vertical shafts 5. 80 To the table 1 are secured the bearings 6 in which is journalled the shaft 7, driven by any suitable connection, from the main drive shaft (not shown) of the fringe making machine. The shaft 7 carries the pulleys 8 85 over which pass the belts 9 which also pass over the pulleys 10 on the shafts 11, to revolve the latter. To the upright 2 is adjustably and detachably secured the clamp 12, which has the vertical stem 13 which carries the coil spring 14, adjusted by the nut 15, to regulate the pressure of the presser foot 16, which presses the work or fringe 17 after the latter has been cut by the cutters 18 on the shafts 19, the work being then propelled 90 forwardly or to the left of Figure 5, by the rollers 20 on the shafts 21 which are provided with the pinions 22. The shafts 19 and 21 are driven by suitable connections 95 from the main driving mechanism (not 100

shown) of the fringe knitting machine, the parts heretofore described being fully illustrated and described in our copending application Serial No. 330,866 filed January 7, 1929.

6 The shafts 11 are journalled in the pendant hanger brackets 24 and carry the bevelled pinions 25 which mesh with the bevel pinions 26 on the lower ends of the shafts 5 to 10 revolve the latter, the inner juxtaposed ends of the shafts 11 being journalled in the common bearing bracket 27 as seen in Figs. 1 and 2. The shafts 5 carry the drums or cylinders 28 which are revolved in the direction 15 of the arrows *a* when the shafts 11 are driven by the pulley 10 and belt 9. To the outer surface of the drums 28 are secured the semi-circular bands 30 by the rivets or the like 31, the bands 30 being spaced from the drums 20 28 thus forming a curved pocket or seat 29 for receiving and engaging the lower portions 33 of the card board core or blank 34 best seen in Figs. 3 and 7.

25 The cores or blanks 34 are made of a flexible cheap material such as card board or the like, and are provided with the upper terminal ears 35, which overhang the body of the core or blank as will be understood from Fig. 3. In Fig. 4 we have shown a retaining pin 30 or clip 36 comprising the upper manipulating or holding knob 37, the lower stem 38 and the flat spring 39, having a rounded bottom end, whereby the core, or blank 34 may be clamped to the drums 28 as will be understood from the dotted lines in Fig. 2, a pair 35 of said pins being employed for each drum as seen in Fig. 1.

30 The operation is as follows:

35 The cores or blanks 34 are positioned on the drums 28 with the lower portions 33 thereof engaging the pockets 29 formed between the bands 30 and the drums 28. The pins 36 are then applied to retain the core or blank 34 in a semi-cylindrical position. The 40 fringe forming machine being started, the driving mechanism thereof drives our novel winding mechanism by the means as heretofore described to revolve the drums 28 in the direction of the arrows *a*, thus winding the 45 fringe 17 formed by the fringe forming machine, upon the outer circumferences of the drum 28 and blanks 34. After a sufficient 50 or predetermined length of fringe has been wound on the pair of blanks, the fringe is 55 severed transversely whereupon the pins 36 are disengaged or pulled upwardly and the card board blanks 34 are withdrawn with the fringe 17 wound therearound and each blank 60 with the fringe thereon straightens out so as 65 to appear as shown in Fig. 6. The ears 35 of the card board blanks 34 serve as handles and as abutments to prevent the upward slipping of the fringe wound therearound, the length 70 of said card board blanks 34 being approximately one half the circumference of the

drums 28, so that when said blanks resume their normal flat position as seen in Fig. 7, the fringe 17 wound around the drums 28 is stretched taut on either side of said blanks as shown in said Fig. 7.

70 It will thus be seen that we have devised novel and simple means for winding the fringe formed by our novel fringe forming machines, automatically, neatly and efficiently, without any manual labor and without in any way interfering with or affecting the construction or operation of the fringe forming machine. It will be sufficiently understood from Fig. 6 that our novel fringe machine, forms a duplex fringe or pair of fringes which before cutting are composed of the doubled or U-shaped parallel tapes 40, around which the transverse filaments are wound transversely as at 41, seen at the right of Fig. 6. The line of stitching 42 is produced by the needles shown diagrammatically at 43 in Fig. 6 and the fringe fabric after being severed on a central median line by the cutters 18, seen at the right of Fig. 5, and in Fig. 6, appears as indicated at 17 at the left of Fig. 6 and in Figs 1 and 6, the fringe filaments falling from the horizontal position seen in Fig. 6 into substantially the vertical position seen in Fig. 5, which they 80 assume during the winding operation.

85 By our novel mechanism, a pair of fringes are simultaneously and expeditiously wound on the cores or blanks, which, when withdrawn from the winding drums, flatten out as seen in Fig. 7, and without further manipulation or attention are ready for the market. We have deemed it unnecessary to describe in greater detail the manufacture of the pair of fringes or the mechanism for propelling the latter to the winding drums or the means 90 for actuating the latter as it is evident that other equivalent means may be employed if desired.

95 It will be seen from Fig. 2 that the bands 30 are about one-half the height of the drums 28 and that the blanks 33 when positioned in the seats 29 extend for their major portion above said seats so that the ears 35 are about coincident with the top of the drums 28, whereby the fringe when wound on said 100 blanks will be neatly positioned thereon substantially as seen in Fig. 7.

105 We are aware that the invention may be embodied in other specific forms without departing from the spirit or essential attributes thereof, and we therefore desire the present embodiment to be considered in all respects as illustrative and not restrictive, reference being had to the appended claims rather than to the foregoing description to indicate the 110 scope of the invention.

115 Having thus described our invention what we claim as new and desire to secure by Letters Patent, is:—

120 1. A winding mechanism for a fringe form-

ing machine, comprising a drum, actuating means therefor, and a semicircular seat in proximity to said drum for the reception of a flexible blank adapted to partially surround said drum and to receive the fringe wound thereupon.

2. A winding mechanism for a fringe forming machine, comprising a drum, actuating means therefor, a semicircular seat formed on said drum, a flexible blank positioned in said seat and partially surrounding said drum, and means for detachably securing said blank within said seat and to the periphery of said drum.

15 3. A winding mechanism for a fringe forming machine, comprising a drum, actuating means therefor, a semicircular band carried by said drum and spaced from the outer circumference thereof, a flexible blank positioned between said band and said drum and means for detachably securing said blank to the periphery of said drum.

4. A winding mechanism for a fringe forming machine, comprising a drum, actuating means therefor, a band surrounding said drum and spaced from the outer circumference thereof to form a curved seat, a flexible blank positioned in said seat between said band and said drum and detachable means for retaining said blank in curved position around said drum.

5. A winding mechanism for a fringe forming machine, comprising a drum, actuating means therefor, a band of lesser height than said drum carried by said drum and spaced therefrom whereby an external annular seat is formed, a flexible blank having its lower portion engaging said seat and its upper portion projecting above said band, and means for detachably securing the upper portions of said blank at opposite points to the periphery of said drum.

6. A winding mechanism for a fringe forming machine, comprising a drum, actuating means therefor, a semicircular band of lesser height than said drum and carried by said drum and spaced therefrom, whereby an external semicircular seat is formed, a semicircular flexible blank having its lower portion engaging said seat and its upper portion projecting above said drum, and means for detachably securing the upper periphery of said blank at opposite points to the upper periphery of said drum.

55 7. In a device of the character stated, a pair of vertically disposed winding drums, semi-circular seats on said drums, means for simultaneously rotating said drums, curved flexible blanks detachably mounted in said seats, and means for propelling a fringe blank towards said drums.

PHILIP KRANZ.
ALBERT P. SCHMID.
